UNITED STATES PATENT OFFICE

127,264

DESIGN FOR A DRESS

Ann Verdi, Jackson Heights, N. Y.

Application April 16, 1941, Serial No. 100,405

Term of patent 3½ years

To all whom it may concern:

Be it known that I, Ann Verdi, citizen of the United States, residing in Jackson Heights, Long Island, in the county of Queens and State of New York, have invented a new, original, and ornamental Design for a Dress, of which the following is a specification, reference being had to the accompanying drawing, forming part thereof.

I claim:

The ornamental design for a dress, substantially as shown.

ANN VERDI.
